UNITED STATES PATENT OFFICE

118,625

DESIGN FOR A MOTION PICTURE PROJECTION HEAD CASING

Oscar Krastel, Columbus, Ohio

Application June 28, 1939, Serial No. 85,745

Term of patent 7 years

To all whom it may concern:

Be it known that I, Oscar Krastel, a citizen of the United States, residing at Columbus, in the county of Franklin and State of Ohio, have invented a new, original, and ornamental Design for a Motion Picture Projection Head Casing, of which the following is a specification, reference being had to the accompanying drawings, forming a part thereof.

Fig. 1 is a perspective view looking toward the right front corner of a motion picture projection head casing showing my new design;

Fig. 2 is an elevational view of the right side;

Fig. 3 is a perspective view looking toward the left rear corner;

Fig. 4 is a view of the left side in elevation.

I claim:

The ornamental design for a motion picture projection head casing, as shown.

OSCAR KRASTEL.
